WASHBOARD SUPPORT FOR BATHTUBS

Ben I. Dilger, Birmingham, Ala.

Application November 27, 1933, Serial No. 699,851

10 Claims. (Cl. 68—29)

My invention relates to a support adapted to hold a washboard in convenient position for use in bath tubs and the like.

As a general rule it is not practicable to utilize washboards for the washing of garments in bath tubs, because the ordinary bath tub is low so that one cannot conveniently work at a washboard set therein, even assuming that a washboard could, without the assistance of a suitable support or brace, be held firmly in proper position for use in the tub.

I have conceived, however, that there is a real need for a simple, inexpensive and effective means by which a washboard can be supported in various sizes and shapes of bath tubs in such manner and in such position that it can be conveniently used by a house wife.

A further object of my invention is to design a holder capable of permitting the washboard mounted therein to be adjusted vertically to suit the user.

A further object of my invention, which is of material importance, is to design the holder so that it will form a marginal brace adapted to be clamped about the wooden frame of the washboard so as to reinforce it, hold its parts firmly together, and protect it, thus greatly extending the life of the washboard and preventing its frame pulling apart or working loose so as to destroy the usefulness of the washboard.

My invention further contemplates the provision of a single iron frame comprising side members connected overhead and braced at an intermediate point by a transverse clamp bolt which can be tightened to cause the frame to tightly clamp itself about the washboard, the frame having sufficient flexibility to accommodate itself to the normal variations in width of standard washboards.

My invention further contemplates associating such a frame with adjustable rear braces which engage a rim of the tub in such manner that when the holder rests on the tub bottom, it will be braced and held firmly in position under use which will support the washboard over the tub so that in using it the bath room floor will not be splashed with soap and water.

My invention further contemplates mounting the rim engaging frame legs on the clamp bolt and providing one or more wing nuts which serve effectively both to clamp the rear brace members in the desired adjustment and to hold them rigidly assembled with the frame.

My invention further contemplates the covering of the feet and rim engaging portions of the

rear brace with rubber sleeves to prevent their slipping or defacing the tub.

My invention further comprises the novel details of construction and arrangements of parts which, in their preferred embodiment only, are illustrated in the accompanying drawing which forms a part of this specification, and in which:

Fig. 1 is a perspective view of the washboard supporting frame work with the washboard removed and the parts set in position ready for use.

Fig. 2 is a side elevation of the support carrying the washboard and set in a bath tub ready for use.

Fig. 3 is an enlarged cross sectional view taken on the line III—III of Fig. 2.

Similar reference numerals refer to similar parts throughout the drawing.

In the embodiment of my invention illustrated, I show a marginal frame work formed of a light angle iron and comprising side legs 5 and 6 connected overhead by a top cross member 7. The base flange of the angle iron on each side is extended beyond the side flanges and bent to provide a curved foot piece 7a which is encased in a rubber sleeve 8. The side flange of the angle irons adjacent to the foot pieces 7a is slit to form a tongue 9 that is bent to provide a stop to limit the downward adjustment of the washboard 10. On the back of the legs of the frame in the lower middle portion thereof I mount two aligned bearings 11 which receive a cross clamp bolt 12, preferably having its ends threaded and projecting sufficiently beyond the side legs 5 and 6 of the frame for each to receive a rear brace leg 13 and a wing nut 14.

These rear brace legs 13 are formed by light bar iron which is twisted and bent down at 15 and then up to form a hook-like extension 16 which is encased in a rubber sleeve 17, it being noted that the hook end 18 drops low enough to provide an ample thrust bearing engagement with the top or rim 19 of the tub so that it will not slip thereover while the washboard is in use.

These legs 13 near their ends carry a cross rod 20 adapted to interlock in the selected notches 21 in the brace arms 22 which are pivoted at 23 to the sides of the frame near their upper ends.

The washboard comprises the customary corrugated rubbing surface 24 and the jointed marginal wooden frame 25. The angle iron sides of the support, in which are seated the side members of the washboard, thus not only hold the washboard, which sets at the desired angle and adjusted position in the bath tub, but also effectively brace

the frame of the washboard so as to give it the maximum life in service.

By reference to this Fig. 3 it will be apparent that the tightening of the wing nuts will act to clamp the rear brace legs 13 tightly against the frame sides like washers so that they will be braced rigidly in their adjusted position with their cross rod 20 engaged in the desired notches 21 of the brace arms 22. Thus assembled, the support can be set in the tub and it will hold the washboard firmly in a very convenient position for washing to be done on it.

The washboard can be adjusted high or low in the frame by loosening the wing nuts and slipping it up or down. When the device is not in use, the wing nuts can be loosened, the rear legs swung down into collapsed position against the frame and the side brace arms swung downwardly until their cross rod engages the frame, when the support will be collapsed into very small space for storage.

It is preferable that the frame be left clamped about the washboard at all times for the protection it will give the latter against warping or working loose.

The design of the rear brace elements and their tub engaging portions will be such as to interfere with the ordinary standard bath tub rim and it will be observed that it is unnecessary for the foot pieces 8 to engage the opposite side of the tub as they will rest with sufficient firmness on the tub bottom to hold the frame in working position.

While I have shown my invention in but one form, it will be obvious to those skilled in the art that it is not so limited, but is susceptible of various changes and modifications, without departing from the spirit thereof, and I desire, therefore, that only such limitations shall be placed thereupon as are imposed by the prior art or as are specifically set forth in the appended claims.

What I claim is:—

1. In a washboard support for bath tubs, an angle iron frame adapted to stand upright in a tub and comprising a top member and side legs having at their lower ends flanges bent to form feet, bearings attached to the back of the frame, a cross bolt mounted in the bearings, a brace arm mounted on each end of the bolt, a wing nut to clamp each arm against the frame sides and the frame sides against the washboard sides, notched members hinged to the frame near its top, and a cross member connecting the brace arms and adapted to engage the notched members, said rear brace arms shaped to form a hook adapted to engage and take a thrust bearing against the rim of the tub.

2. The combination with a complete washboard, of a frame for supporting same in upwardly inclined position offset from the rim of a bath tub, comprising upright frame supports adapted to rest on the bottom of the tub and having means to clamp the washboard thereto free for vertical adjustment thereon, and brace means adjustably connected to said supports and adapted to engage over, and take a thrust bearing from the inside against the tub rim to hold the washboard braced in offset relation to said rim.

3. The combination with a washboard having a wooden marginal frame, of a metallic support for said washboard comprising an upwardly inclined metal frame in which the washboard frame is adapted to be embraced, means to clamp said metal frame about the wooden frame to

brace the latter, said metal frame having side legs extending downwardly beyond the bottom of the wooden frame and adapted to rest on, and support the washboard substantially spaced above, the tub bottom, and rear braces adjustably connected to said metal frame and adapted to engage over and take an inner thrust bearing against a side wall of the bath tub to support the washboard substantially offset therefrom and elevated above the tub bottom.

4. In a device of the character described, the combination with a washboard and its frame, of a supplemental frame for supporting the washboard upright comprising side angles set to receive the washboard frame between them free for upward adjustment therein and elongated to project below the washboard sides to form supports therefor, a cross clamp means comprising a transverse bolt extending through the frame behind the washboard carrying a clamp nut adapted to bind the metallic frame angles against the washboard frame to brace and reinforce the latter and hold it in desired adjusted position, and braces connected to the supplemental frame and adapted to engage over and take a thrust bearing against the inner side of the tub rim to support the washboard in offset relation thereto, said braces comprising pivoted members mounted on the end of said bolt and adapted to be held in set position against the frame by said clamp nut.

5. The combination with a complete washboard, of a supplemental frame for bracing the washboard in upright position in a bath tub, comprising side members secured to the sides of the washboard frame and extending downwardly beyond same to form feet adapted to rest on the bottom of the tub and support the washboard in elevated position above same, and a pair of adjustable braces connected to each side member of the supporting frame and having a cross tie member near their free ends, said ends comprising members adapted to engage over, and take a thrust bearing against the inner side of, the tub rim.

6. A device according to claim 5, in which each pair of brace members comprises a lower member to which the cross tie is connected and the outer ends of which are deformed to produce the rim engaging elements, said lower member being pivoted on the frame and having clamp means to lock it in adjusted positions, and the other brace of each pair being notched to engage the cross tie in different adjusted positions.

7. A frame for supporting a washboard in upright position in a bath tub, comprising side legs adapted to rest on the tub bottom, means engaging said legs and adapted to attach a washboard thereto, and relatively adjustable interlocked brace members on the back of the frame which comprise hook ends adapted to fit over the tub rim and provide an inner thrust bearing to hold the washboard in offset relationship from said rim.

8. A frame for mounting a washboard in a bath tub in upwardly inclined position, comprising side members having greater length than the washboard and adapted at their lower ends to rest on the tub bottom and at their upper ends having brace elements, means to adjustably engage said brace elements which comprise hooks adapted to fit over the tub rim and present a thrust shoulder against the inner side of the rim to hold the frame firmly inclined and offset from the tub rim, and clamp means engaging said side members and adapted to secure the washboard in

position between them free for vertical adjustment.

9. A frame for supporting a washboard in upright position in a bath tub, comprising a U-shaped frame having angle iron sides and rubber covered feet adapted to rest on the bottom of the tub, said frame being adapted to permit a washboard to set between and be upwardly adjusted relatively to said frame, a cross clamp member adapted to bind the washboard in adjusted position, upwardly inclined brace arms carrying hooks adapted to engage over the tub and shaped to

provide a thrust bearing against the inner face of the tub, and complementary brace members carried by the upper portion of the frame and adapted to cooperate with the lower braces and hold the frame and washboard offset from the tub rim. 5

10. A frame according to claim 7, in which the braces are adapted to hold the washboard upwardly inclined with its upper end above but spaced inwardly of the tub with relation to said tub rim. 10
